UNITED STATES PATENT OFFICE

2,395,918

FUEL MANIFOLDING MEANS FOR
RADIAL CYLINDER ENGINES

John Stucke, Philadelphia, Pa.

Original application June 19, 1940, Serial No. 341,375. Divided and this application March 19, 1943, Serial No. 479,766

2 Claims. (Cl. 123—44)

My invention relates to improvements in fuel manifolding means for radial cylinder internal combustion engines of the type exemplified in my copending application Serial No. 341,375, filed June 19, 1940, now Patent Number 2,330,528 of September 28, 1943, and of which the instant application is a division.

By way of explanation, in the type of internal combustion engine with which my improvements are particularly concerned, the cylinders are mounted in radial position in a cylindrical casing and revolve together with the casing about a crank shaft and oppositely relative to the direction of rotation of the crank shaft.

It is the primary object of the instant invention to equip such engine with practical, simply constructed, and highly efficient means for introducing an explosive mixture into the cylinder of the engine.

Other and subordinate objects are also comprehended by my invention, all of which, together with the precise nature of my improvements will be readily understood when the succeeding description and claims are read with reference to the drawings accompanying and forming part of this specification.

In said drawings:

Figure 1 is a view in vertical longitudinal section of a radial cylinder internal combustion engine equipped with my improvements,

Figure 2 is a view in transverse section,

Figure 3 is a detail view with parts in section of the gearing, and

Figure 4 is a view in elevation of the stationary cam carrying member.

Referring to the drawings by numerals, the letter A designates the cylindrical casing of the engine and which is supported for rotary movement, in any suitable manner, on a base frame, a part of which is shown in Figure 1 and designated by the numeral 2. The casing A carries a plurality of cylinders 3 radially arranged therein to extend therefrom in pairs in diametrically opposite position in each pair, the pairs being laterally offset and circumferentially staggered relatively. The inner ends of the cylinders 3 extend into the casing A and are suitably attached to the latter. Each cylinder 3 is provided with a cylinder head 5 carrying a spark plug 6 and each head 5 is provided with an intake passage 7 and an exhaust passage 8. The intake passages 7 are connected by manifolds 9, and the exhaust passages 8 by exhaust manifolds 10. The inlet valves are shown at 11, and the exhaust valves at 12.

The pistons 13 are connected, by connecting rods 14, to cranks 15 of a crank shaft 16 journaled in one end of the casing, as shown at 17, and having its other end journaled in a partition 18 in the casing, as shown at 19. A gear 20 is fastened to that end of the crank shaft 16 which is passed through the partition 18 and a second partition 21 extends across the casing A and carries bearings 22 for a number of stub shafts 23 each of which has a gear 24 on one end meshing with a gear 20 of the crank shaft. A pinion 25 is carried by the other end of each shaft 23 for meshing with a stationary gear 24' on a stationary hub 25 passing through an end of the casing A and attached to the frame part 2, as shown at 26. This arrangement of gearing causes both the casing A and the crank shaft 16 to rotate but in opposite directions relatively.

Coming now to my improved manifolding means, a tubular shaft 7 passes through the center of the partition 21 and also through a tubular part 28 which is rotatably arranged in the stationary hub 25. A carburetor, shown at C in dotted lines in Figure 1, is in communication with the tubular member 27, and branches 29 extend from the inner end of the tubular member 27 through parts of the casing A and connect with the inlet manifolds 9 so as to supply explosive mixture to the cylinders 3.

Returning now to the valves 11, 12, and in further explanation of the operation of the engine, each valve is actuated by a bell crank 30 pivotally supported in the casing A, with one arm of the bell crank engaging the valve stem and its other arm being engaged by a rod 31 slidably mounted in a sleeve 32 in the partition 21. A second bell crank 33 is pivotally supported by a circular portion 34 in the casing A and is engaged by a rod 35. The rods 35 are engaged by the cams 36 on the stationary hub 25, the arrangement being such that said cams will actuate the valves in the proper manner during rotation of the casing A and the rods 35 with said casing.

The casing A carries brackets 40, each of which includes an angle arm 41 having free portions extending inwardly toward the stationary hub 25 and equipped at the terminals thereof with contact rollers 42. The stationary part 25 has mounted thereon a housing 43 having a contact part 44 in its upper end for engagement by the rollers 42 as the latter rotate with the casing A. A plunger 45 is slidably arranged in the housing 43 and in a part of the stationary hub 25 or member 25 and has its inner end seated in a

cam groove 46 formed in the tubular member 28, the cam 46' formed by the bottom of said groove engaging the plunger 45 so as to complete a circuit, not shown, to a spark plug 48 each time the high part of the cam engages the plunger, and a roller 42 engages the contact member 44. It is not deemed essential to a proper understanding of the present invention to describe the order in which the cylinders 3 fire.

An exhaust ring 49 is suitably mounted in stationary position at one end of the casing A and in surrounding relation to said casing and the exhaust manifolds 10 are suitably arranged to exhaust into said ring. The numeral 50 designates the fly wheel on the crank shaft 16 and within the casing A.

The foregoing will, it is believed, suffice to impart a clear understanding of my invention without further explanation.

Manifestly, the invention, as described is susceptible to modification without departing from the inventive concept, and right is herein reserved to such modifications as fall within the scope of the appended claims.

What I claim is:

1. Means for introducing explosive mixture into the cylinders of a rotary internal combustion engine of the type including a cylinder carrying

rotary crank case, a rotary crank shaft extending through one end of the crank case, and a stationary hub extending through the opposite end of the crank case, said means including a tubular member passing through the stationary hub for rotary movement therein and having an inner end fixed in the crankcase, means for introducing an explosive mixture into the outer end of the tubular member, and conduits fixed to and leading from the inner end of the tubular member out of the crankcase and to the cylinders carried by the rotary crank case.

2. Means for introducing explosive mixture into the cylinders of a rotary internal combustion engine of the type including a cylinder carrying rotary crank case, a rotary crank shaft extending through one end of the crank case, and a stationary hub extending into the opposite end of the crank case, said means including a tubular member passing through the stationary hub for rotary movement and into said crank case, means for introducing an explosive mixture into the outer end of the tubular member, and conduits fixed to and leading from the inner end of the tubular member out of said crank case and each terminating in a manifold connected to a pair of cylinders.

JOHN STUCKE.
